LIGHTING FIXTURE LENS

Viktor Schreckengost, Cleveland, Ohio, assignor
to Holophane Company, Inc., New York, N. Y.,
a corporation of Delaware

Original application April 24, 1953, Serial No.
24,651. Divided and this application August
27, 1953, Serial No. 26,606

Term of patent 14 years

(Cl. D48—16)

To all whom it may concern:

Be it known that I, Viktor Schreckengost, a citizen of the United States of America, and a resident of Cleveland, in the county of Cuyahoga, in the State of Ohio, have invented a new, original, and ornamental Design for a Lighting Fixture Lens, of which the following is a specification, reference being had to the accompanying drawings, forming a part thereof.

In the drawings:

Fig. 1 is a bottom plan view of a lighting fixture lens showing my new design;

Fig. 2 is a top plan view thereof;

Fig. 3 is a fragmentary cross-sectional view to a larger scale taken on the line 3—3 of Fig. 2; and

Fig. 4 is a fragmentary cross-sectional view to a larger scale taken on the line 4—4 of Fig. 2. This application is a division of my co-pending application, D. 24,651, filed April 24, 1953.

I claim:

The ornamental design for a lighting fixture lens, as shown.

VIKTOR SCHRECKENGOST.
